UNITED STATES PATENT OFFICE.

ELMER L. VAN DRESAR, OF ST. PAUL, MINNESOTA, ASSIGNOR TO THE RAIL JOINT COMPANY, OF NEW YORK, N. Y., A CORPORATION OF NEW YORK.

RAIL-JOINT.

1,311,303.

Specification of Letters Patent. Patented July 29, 1919.

Application filed April 26, 1919. Serial No. 292,855.

To all whom it may concern:

Be it known that I, ELMER L. VAN DRESAR, a citizen of the United States, residing at St. Paul, in the county of Ramsey 5 and State of Minnesota, have invented certain new and useful Improvements in Rail-Joints, of which the following is a specification.

This invention relates to an improvement 10 in rail joints, particularly of the continuous type, whereby the full clamping and supporting effect of the joint bar are conserved while there is also provided an effective easement for the rail wave motion through the 15 joint.

An important consideration in designing 20 a rail joint is to provide a joint bar having structural characteristics to effectively resist the acting and re-acting forces due to the wave motion in track, and to provide appropriate compensation for that wave motion. It is a well known fact that the engine load causes a compression of the ties and ballast and of the underlying road bed 25 to an appreciable degree a substantial distance in advance of the rail joint location. This force is first manifested in an upward bending or lifting of the rail followed by a sudden depression, resulting in the wave 30 motion in track, which precedes the rolling load. Accordingly, a most desirable and practical requisite for a track joint is that it shall be flexible enough to pass the advance wave through the joint without breaking 35 the rail within its limits, yet being sufficiently strong to resist the bending moment both upward and downward, of trains passing at the highest speeds. It is therefore the purpose of the present invention to 40 provide a rail joint responding as nearly as practicable to this requisite or requirement, having particularly in view a provision within the rail joint which will relieve the joint, as well as the rail, from the excessive strains due to the upward bending 45 or lifting of the rail as caused by the advance wave in the track, thereby greatly minimizing the danger of breakage of joint plates or breakage of the rail within the 50 joint.

With these and other objects in view which will be readily apparent to those familiar with the art, as the specific character of the invention is better understood, 55 the same consists in the novel construction,

combination and arrangement of parts hereinafter more fully described, illustrated and claimed.

While susceptible of embodiment in different structural shapes a preferred and 60 practical form of the invention is shown in the accompanying drawings, in which:—

Figure 1 is a diagrammatic elevational view showing, by slight exaggeration, the advance wave causing upward bending or 65 lifting of a rail end within the joint.

Fig. 2 is an inside elevation of a rail joint bar, of the continuous type embodying the improvement contemplated by the present invention—showing by dotted lines the rail 70 bearing faces.

Fig. 3 is an end view of the form of bar shown in Fig. 2.

Figs. 4, 5 and 6 are similar cross-sectional views illustrating the normal relation of the 75 bar to the rail bearing faces at different points throughout the length of the bar.

Like references designate corresponding parts in the several figures of the drawings.

In carrying forward the invention the improvements herein specified and claimed are particularly applicable to the well known continuous type of rail joint bar, that is, a joint bar having a rail supporting base member engaging beneath the rail base 85 and integrally joined with an upright member fitting the fishing space of the rail and having a bearing contact with the under side of the rail head and with the upper side of the rail flange. The exact section 90 or shape of this bar is not material to the present invention, nor the particular distribution of metal therein, as the particular feature of improvement upon which this application is predicated is primarily intended to be associated with a rail joint bar comprising, generally, an upright member 1 having an upper head portion 2 for engaging beneath the rail head, a foot flange 3 which overlies and contacts with the rail flange, and an integral inwardly extending rail supporting base member 4. As found in the continuous bar this base member 4 underlies and engages the base of the rail and combines with the inclining foot flange 100 3 to provide therebetween the flange holding groove 5 for the base flange of the rail.

As above indicated, the present invention contemplates fully preserving all of the desirable features and functions of the continu- 110

ous bar whereby the full clamping and rail supporting effect of the bar will be maintained in service, while the added feature of improvement will permit of a free wave motion through the joint so as to relieve, to the greatest extent possible, the strain on the top chord of the bar due to the reflex action. Also to ease the strain on the rail flange due to the upward wave motion which is communicated to the rail end.

The base supporting type of rail joint, to which the present invention is applied, embodies in its general organization the head, 2 provided at the top thereof with the centrally located permanent rail engaging bearing surface A, and at opposite sides of the said permanent bearing surface with the inclined rail-clearance easement surfaces B—B which incline downwardly from the central 20 surface A to the end of the bar. The term "permanent" is applied to the central rail engaging bearing surface A, since that surface retains its substantially level or horizontal characteristic, and is intended to constitute the normal rail supporting surface at the top of the joint bar which engages beneath the heads of both rail ends within the joint. The downwardly sloping top easement surfaces B—B along the end portions 30 of the bar are normally out of contact with the under sides of the heads of the rail, but permit downward flexing of the rails within at end portions of the joint to accommodate the rails to the downward movement of the 35 wave. Thus, it will be noted, from another structural aspect, that a bar having the permanent and clearance surfaces A and B respectively, will be of full section and fishing height at its center but of reduced section 40 and fishing height at the end portions thereof thereby adapting the bar to one phase of the wave motion of the track.

As a necessary complement to the surface formation at the top of the joint bar, the 45 upper side of the base member 4 thereof is correspondingly formed. That is to say, the base member is provided at its intermediate or central portion with the upper permanent rail engaging bearing surface C which per- 50 manently and flatly engages the under side of the rail bases, and at opposite sides of said intermediate or central surface C with the sloping or downwardly inclining rail clearance easement surfaces D—D. These easement surfaces D—D incline or slope down- 55 wardly from the central permanent bearing surface C toward the ends of the joint bar and thereby accommodate the same downward easement for the rails within the ends 60 of the joints, as provided for by the top easement surfaces B—B along the end portions of the bar. As a further complement of the permanent and clearance easement surfaces referred to, the present invention 65 involves the distinctive improvement of pro-

viding the foot flange 3, at its under side, with an intermediate or centrally located upwardly dished rail clearance easement recess or space E. The centrally located easement recess E is disposed within a vertical 70 plane intersecting the permanent bearing surface A at the top of the bar and the permanent bearing surface C at the top of the rail supporting base member, and at opposite sides of said central easement recess or clear- 75 ance space E the under sides of the foot flange 3, (forming the top wall of the flange groove or way 5) is provided with the permanently-engaged rail-engaging bearing surfaces F which have a bearing engagement 80 or contact with the upper side of the rail flange and maintain the generally level or horizontal characteristic common to permanent rail-engaging or rail-contacting surfaces.

The depth of the recess or clearance E is properly proportioned to the extent of the clearance made by the surfaces B—B and D—D so that proper freedom is permitted for the wave motion of the rail in the joint, 90 so as to relieve both the rail and joint bars from the excessive strains due to the well known "pumping action" caused by the track wave which precedes the engine load. And, in that connection, it will have been 95 observed that the upwardly dished recess or clearance E is located precisely at the center of the joint where the ends of the rails are disposed, thereby accommodating the upward movement of the rail base as the 100 rail end bends or lifts upwardly due to the first impulse of the engine load as indicated by the diagrammatic illustration of Fig. 1, while at the same time not interfering with the reflex action of the downward wave motion when the rail end takes its seat on the permanent rail supporting bearing surfaces 105 A and C.

From the foregoing it is thought that the construction and advantages of the herein 110 described improvement will be readily apparent to those familiar with the art without further description, and it will be understood that changes in the form, proportion, and minor details of construction may 115 be resorted to without departing from the spirit or sacrificing any of the advantages of the present invention.

I claim:

1. A rail joint bar having rail head clearance toward its ends, and a rail flange clearance at the central part of the under-side of its foot flange.
2. A continuous type rail joint bar having rail head clearance at the end portions thereof and a central rail flange clearance at the underside of its foot flange.
3. A continuous type rail joint bar having centrally located permanent rail engag- 130 ing bearing surfaces at the top of its head

and at the upper side of its base member, and with rail clearance easement surfaces extending toward the ends from said permanent surfaces, said bar also having a centrally disposed rail flange clearance in the underside of its foot flange.

4. A continuous type rail joint bar having centrally located permanent bearing surfaces respectively at the top of its head, and at the upper side of its base member, and with rail clearance easement surfaces extending toward the ends of the bar from said permanent surfaces, said bar being further provided with an upwardly dished 10 easement recess or clearance in the central portion of the underside of the foot flange.

5. A continuous type rail joint bar provided with permanent rail engaging bear-

ing surfaces centrally of the top of the head and the upper side of the base member and along the end portions of the underside of the foot flange, the foot flange being further provided at the central part of its underside with an upwardly dished easement recess or space.

6. A rail joint bar having a foot flange provided centrally at the underside thereof with a clearance portion permitting easement for the upward wave motion of the rail ends within the joint.

In testimony whereof I hereunto affix my signature in the presence of two witnesses.
